UNITED STATES PATENT OFFICE

HENRY M. KEITH, OF HARRISBURG, ILLINOIS

OIL AND LIQUID DISPENSING DEVICE

Application filed February 23, 1932. Serial No. 594,627.

This invention relates to liquid dispensing devices and has for the primary object, the provision of a device of the above stated character for easily and quickly dispensing liquids of any desired character without waste and in predetermined amounts and which is so constructed as to efficiently display the liquid to the purchaser prior to being dispensed.

Another object of this invention is the provision of a dispensing device operated by air pressure, whereby liquid may be forced from a supply to a visible measuring receptacle and dispensed therefrom under pressure in desired amounts.

A further object of this invention is the provision of means whereby the dispensing medium may be employed for actuating a control means for either placing the liquid in the supply under air pressure or the liquid in the liquid measuring receptacle under pressure and to automatically vent the receptacle when filling the latter from the supply.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a liquid dispensing device constructed in accordance with my invention.

Figure 2 is a fragmentary vertical sectional view illustrating the same and taken on the line 2—2 of Figure 1.

Figure 3 is a detail sectional view taken on the line 3—3 of Figure 2.

Figure 4 is a transverse sectional view taken on the line 4—4 of Figure 1.

Figure 5 is a detail sectional view taken on the line 5—5 of Figure 2.

Figure 6 is a fragmentary sectional view illustrating a check valve for the liquid intake pipe from the supply to the measuring receptacle.

Referring in detail to the drawings, the numeral 1 indicates a tank or drum for containing lubricating oils or any other liquid offered for sale and has associated therewith a dispensing device 2 which includes a base 3 supporting a transparent bowl or cylinder 4, the upper end of which is closed by a head 5 provided with a clean-out port 6 normally closed by a removable cap 7. Suitable leak-proof connections are provided between the ends of the cylinder 4 and the head 5 and base. The base is provided with a centrally located passage 8 therethrough and in which is formed a valve seat 9 normally closed by a self-seating valve 10. The passage 8 is connected to a supply pipe 11 extending through a suitable stuffing gland 12 of a supply tank or the supply drum 1. The passage 8 is intercepted by a horizontally disposed chamber 13 in which a tube 14 is journalled and one end of said tube extends exteriorly of the base by way of a stuffing box or gland 15 and has secured thereto a hollow arm 16 and the latter being in communication with the tube 14 by ports 17. A hollow angularly disposed journal 18 is formed on the arm 16 and has journalled thereon a coupling 19, the latter being in communication with the extension 18 by the ports 20 and is connected to a hose or similar element 21. The free end of the hose 21 carries a dispensing nozzle 22 provided with a manually controlled valve 23 whereby the liquid of the cylinder 4 may be dispensed in desired amounts.

The hollow arm 16 is normally maintained in a vertical position as shown in Figure 1 by a coiled spring 24 attached to a bracket 25 on the base and when in this position, the tube 14 is so arranged that a projection 26 is disengaged from the valve 10 allowing the latter to remain in a seated position interrupting the passage between the drum 1 and the cylinder 4.

The base 3 has formed therein an air chamber 27 suitably connected to an air pressure source and has located therein a control valve 28 of the rotary type and is actuated by the rotation of the tube 14 by having the movable element 29 thereof connected to the tube by a stem 30. The valve 28 is pro-

vided with outlet ports 31 and 32, the latter named port connected to a pipe 33 which is in turn connected to the drum. The port 31 is connected to a pipe 34 that is in communication with the cylinder 4 by way of a port or passage 35 in the head 5. The head 5 is also provided with a vent opening 36 having a valve seat 37 and the latter has associated therewith a self-opening valve 38 normally held in a seated position by a rocker arm 38' pivoted to a bracket 39 carried by the head. The rocker arm 38' is pivoted to a push rod 40 slidably mounted in a guide 41 with its lower end in engagement with the arm 16 so that when said arm 16 is disposed vertically, the rocker arm 38' will seat the valve 38 and close the cylinder 4 to the atmosphere.

A float 42 is slidably mounted in the cylinder 4 and is provided with washers 43 having frictional contact with the walls of the cylinder. The float is adapted to ride upon the liquid within the cylinder, it being understood that the cylinder 4 in conjunction with the base and head 5 forms a visible measuring receptacle, the cylinder 4 being provided with suitable graduations to indicate the amounts of liquid contained within the measuring receptacle.

The lower end of the supply pipe 11 is provided with a suitable check valve 44 which will permit liquid to pass from the drum to the measuring receptacle but which will prevent the liquid from returning to the drum.

In operation when desiring to force the liquid from the drum to the measuring receptacle, the hollow arm is swung in the arc of a circle against the action of the spring 24 by exerting a pull on the hose. This movement of the arm imparts a movement to the tube 14 unseating the valve 10 and at the same time connecting the air pressure from the chamber 27 to the drum and the air pressure displaces the liquid from the drum into the measuring receptacle. As soon as the hose is manually released, the spring returns the arm 16 to a vertical position cutting off the supply of air pressure to the drum and allowing the valve 10 to seat. The valve 31 then assumes a position to establish communication between the air pressure means and the upper end of the cylinder 4 by way of the pipe 34 placing the liquid in the cylinder under pressure by the air pressure acting

against the float 43, so that when the valve 31 is manually opened liquid will be rapidly forced from the cylinder. The float moving downwardly in the cylinder wipes the liquid from the walls of the cylinder. When the arm 16 is positioned to admit liquid to the cylinder 4 from the drum 1, the valve 38 is unseated allowing the cylinder 4 to be vented.

While I have shown and described the preferred embodiment of my invention, it will be understood that minor changes in con-

struction, combination and arrangement of parts may be made without departing from the spirit and scope of my invention, as claimed.

Having thus described my invention, what I claim is:

1. A liquid dispensing device comprising a visible measuring receptacle, means connecting said receptacle to a liquid supply, means for admitting air pressure to either the liquid supply or the receptacle, and a dispensing means for said receptacle and capable of actuating the means for admitting air pressure to the liquid supply or the receptacle. 75

2. A liquid dispensing device comprising a visible measuring receptacle, a supply pipe in communication with the receptacle and a liquid supply, a self-closing vent valve for the receptacle, an air pressure means connected to the receptacle and the liquid supply, a control valve for the air pressure means, and a dispensing means for said receptacle capable of unseating the self-closing vent valve and for actuating the air pressure control valve to admit air pressure either to the liquid supply or to the receptacle. 80

3. A liquid dispensing device comprising a visible measuring receptacle, a pipe connected to the receptacle and to a liquid supply, a self-closing valve for the pipe, a rotatable tube in communication with the receptacle, a hollow arm carried by and in communication with the tube, a dispensing means connected to said arm, an air pressure means connected to the receptacle and to the liquid supply, a control valve for said air pressure means actuated by the rotation of the tube, means carried by the tube for unseating the self-closing valve on movement of the tube in one direction, a self-opening vent valve for the receptacle, means associated with the self-opening valve for seating the latter by the arm when in a given position, tension means for normally maintaining said arm in the last named position, said air control valve normally establishing communication between the receptacle and the air pressure means, said tube adapted to be moved in one direction for unseating the self-closing valve and actuating the air control valve to admit air pressure to the liquid supply when the arm is moved by a pull on the liquid dispensing means. 95

In testimony whereof I affix my signature.

HENRY M. KEITH. 120
